UNITED STATES PATENT OFFICE.

HELEN DOROTHY MILLS, OF EAGLE ROCK, CALIFORNIA.

DESIGN FOR A DOLL.

Application filed November 26, 1923. Serial No. 7,838. Term of patent 3½ years.

To all whom it may concern:

Be it known that I, HELEN DOROTHY MILLS, a citizen of the United States, residing at Eagle Rock, county of Los Angeles, and State of California, have invented a new, original, and ornamental Design for Doll, of which the following is the specification, reference being had to the accompanying drawing, forming a part thereof.

I claim:

The ornamental design for a doll, as shown.

HELEN DOROTHY MILLS.
